DISTRIBUTOR FOR PULVERIZED COAL
FEEDING SYSTEMS

Joseph E. Kennedy and Herbert W. Johnson, New York, N. Y., assignors, by direct and mesne assignments, to Nellie Kennedy, New York, N. Y.

Refiled for abandoned application Serial No. 337,230, February 4, 1929. This application July 10, 1930, Serial No. 467,284.

2 Claims. (Cl. 302—28)

This invention relates to the distribution of pulverized fuel, such as coal, transported or conveyed in an air stream from a source of supply, as pulverizing apparatus or a storage bin, to a place of combustion, as a burner or burners leading into the combustion chamber of a furnace or furnaces, the application being a substitute for our application filed February 4, 1929, Serial No. 337,230.

It is the object of the present invention to effect a distribution of the stream of a main conduit to branch conduits so that each of the branch streams will have substantially the same volume or density of the pulverized material or solids, and to provide means for this purpose which is simple in construction and efficient in operation.

In the drawings accompanying and forming a part of this application there is shown an embodiment of the invention wherein Figure 1 is a longitudinal sectional view showing the same interposed between a main conduit and branch conduits leading therefrom.

Figure 2 is a view looking at the bottom of Figure 1 partly in section to show the arrangement of a fluid pressure motor for actuating the same; and

Figure 3 is a cross sectional view taken on the line 3—3 of Figure 1 looking in the direction of the arrows to show the arrangement of the means for connecting the branch conduits with the main conduit through the improved distributor means.

In the drawings there is illustrated an embodiment of the invention shown interposed between and in the connection of a main conduit with branch conduits in a pneumatic system for the transporting or conveying of pulverized coal in suspension in an air stream from a source of supply, which may comprise a pulverizing apparatus or a storage bin, to a burner or burners for combustion in a furnace or furnaces, the pulverized material in suspension in the air stream being delivered by a fan (not shown) to a main conduit 4 and distributed from said conduit to a plurality of branch conduits 5, in the present instance shown as three in number, to the outlet ends of which branch conduits the burners are connected.

In pulverized coal feeding systems of this character difficulty has been experienced in the distributing of an air stream from the main conduit to branch conduits in maintaining the respective branch streams with an equal density of the pulverized material or solids, there being

a tendency in the passage of the stream through the main conduit for the solids to assume an unequal distribution throughout the cross section of the stream with the result that the stream is composed of strata having different density of pulverized material or solids, and in the distribution of the main stream to the branch streams this unequal density of the solids is maintained with the result that the branch streams do not have the same density of the combustible solids and a branch stream or streams may be so deficient in combustible solids that proper combustion will not take place at the burner.

This disadvantage is overcome by the present invention by opening and shutting off communication between the main and the branch conduits, and directing and delivering the stream from the main to the branch conduits, in intermittent sequence. For this purpose the branch conduits are connected with the main conduit by a casing of truncated conical form open at the smaller end and having a cylindrical portion 7 at said end whereby it is connected with the main conduit 4 in co-axial and concentric relation by engaging and securing the cylindrical portion of the casing in a flanged collar 8, the flange of which collar is adapted to abut the flange of a collar 9 mounted upon the main conduit and securing the collars together by bolts passed through openings in the collar flanges. A plate 10 of larger diameter than the larger end of the casing is secured to said end of the casing by bolts engaging in openings in said plate and a ring 11 mounted upon said end of the casing. The plate has a series of openings 12 equal in number to the number of the branch conduits to be connected with the main conduit, in the present instance three in number, said openings being substantially of segmental form and circumferentially disposed about the axis of the casing with the outer and inner walls arranged in concentric arcs and the outer wall arranged in line with the wall of the casing. The branch conduits are connected with the openings in said plate by connectors having a portion 13 and at which end they are connected with the plate 10, the entrance to the passage through the connectors at said end being shaped to conform to the openings in the plate 10 with the opposite end walls converging to a cylindrical portion 14 at the opposite end to which the branch conduits 5 are connected. The casing may be supported by connecting extended portions thereof to the beams of a supporting structure, as at 15.

The means operative for opening and shutting

55

off communication between the main and branch conduits to direct and deliver the stream from the main conduit to the branch conduits in intermittent sequence is arranged in the casing 6, and 5 comprises a second casing 16 revolvably mounted in and shaped to conform to the casing 6 and with the walls of the casings in slightly spaced relation. The casing 16 has a cylindrical portion 17 arranged in overlapped relation to a cylindrical portion 18 extended from a conical portion 19 of a sleeve and the latter portion having a laterally extending flange whereby the sleeve is supported by clamping the sleeve flange between the flanges of the collars 8, 9, the sleeve constituting a continuation of the main conduit 4. The larger end 10 of the casing 16 is closed by a plate 20 arranged with an opening 21 by cutting a recess in the peripheral portion of the plate shaped to conform to the opening 12 in plate 10, said opening being eccentric to the axis of the casing and by the revolving of the casing moved in an orbit coincident with the openings 12 so that said opening is brought in intermittent sequence into communication with the openings 12, the closure plate 20 15 operating through the revolving of the casing to shut off the branch conduits in intermittent sequence. A partition plate 22 is secured within and extends longitudinally and diagonally of the casing 16, one end of said partition being shaped 20 to extend about and secured to the inner and end walls of the opening 21, as at 23, and the opposite end wall terminating at the juncture of the conical portion with the cylindrical portion of the casing 16 and shaped to conform to the cylindrical portion, as at 24, and the opposite marginal side portions of said partition plate engaging opposite wall portions of the casing. The partition 25 forms a continuous passage through the casing 16 forming in effect a revolvable conduit.

30 The casing 16 is revolvably mounted in the casing 6 by a hub 25 fixed axially in an opening in the plate 20 to extend from opposite sides thereof and engaged upon the end of a shaft 26 and keyed thereto, as at 27, to rotate with the shaft and held against axial movement on the shaft by set 35 screws 28. The shaft is journalled, preferably by anti-friction bearings 29, 29', in the bore of a sleeve or bearing member 30 fixed to the closure plate 10 for the casing 6. The shaft is held against axial displacement by seating the one bearing 29 against a shoulder formed by a reduced portion of the bore extended through the end of the sleeve and a shoulder on the shaft engaged by said bearing, and the other bearing 29' abutting a shoulder 40 on the shaft and retained in the sleeve bore by a nut 31 threaded into the top of the sleeve bore in abutting relation to the bearing 29'. By this arrangement of bearing mounting there is provided a space within and between the sleeve and shaft 45 which may be packed with lubricant, and to prevent the lubricant from oozing out from the bearing a stuffing box is arranged at one end of the bearing and the nut 31 carries packing in a recess therein.

50 Means are provided to rotate the shaft and thereby the casing 16, shown as a fluid pressure motor, comprising a cap shaped casing 32 carried by the bearing member or sleeve 30, the open end of which is closed by a plate 33. The shaft is extended into the casing through a stuffing box 34 with the rotor of the motor, comprising a wheel 55 having vanes or pockets disposed about the periphery, mounted on the reduced end of the shaft within the casing, by keying and a nut 35 threaded onto the shaft. The casing is arranged

with openings 36, shown as three in number, for the passage of the motive fluid, said openings being through the peripheral wall of the casing and arranged in a plane tangential to the periphery of the rotor. These openings are in line with openings through bosses 37 arranged for the removable mounting therein of connection means 38 for conduits for connecting the motor with a source of motive fluid. The motive fluid is expended from the casing through a conduit connected with an outlet 39 centrally through the plate 33.

5 In the distributing and feeding of pulverized coal in suspension in an air stream and the delivery of the same for combustion to a plurality of burners in pulverized coal feeding systems the pulverized coal is drawn from the source of supply by a fan and delivered by the fan in a single stream or column to a main conduit, and the stream from said conduit is split or separated and delivered to a plurality of branch conduits connected with said main conduit, and to which branch conduits the burners are connected. In such delivery systems there is so much back pressure exerted on the fan with the result that not 10 only is considerable power required to operate the fan but the fan becomes quickly worn requiring the replacing of the same. By the arrangement of the distributor 16 the stream from the main conduit in delivering the same to the branch conduits is 15 not separated but the entire volume of the stream is delivered to each of the branch conduits as successive impulses. As the distributor is revolved and communication is established between the main conduit and a branch conduit through an 20 opening 12 in the plate 10 the other openings through said plate, and thereby the other branch conduits, are shut off from the main conduit by the plate 10 effectively preventing pressures in the branch conduits from exerting back pressure 25 upon the fan, thereby not only requiring less power to operate the fan but assuring the delivery of a stream to each of the branch conduits having an equal density of solids. Furthermore, by the connecting of the main conduit in intermittent sequence with the branch conduits the delivery of the material to and through the branch conduits is in effect by impulses or impelling forces, which operate to reduce to a minimum the 30 tendency of creating back pressure forces not only in the branch conduits but also in the main conduit.

40 While we have illustrated and described one embodiment of means for carrying out the invention it will be obvious that various modifications 45 may be made in construction and arrangement of parts, and that portions of the invention may be used without others and come within the scope 50 of the invention.

55 Having thus described my invention, I claim:

1. In means for distributing a pulverized material carrying air stream into a plurality of branch streams, a main conduit, a casing connected with the main conduit and having a plurality of outlet 60 openings adapted for connection of branch conduits thereto, continuously revolving means in the casing at all times in communication with the main conduit and operative to connect and shut off the main conduit with the outlets of the casing in successive sequence, and a fluid pressure motor mounted on the exterior of the casing and having an operative connection with the revoluble means to actuate the same.

65 2. In means for distributing a pulverized material carrying air stream into a plurality of 70

branch streams, a main conduit, a casing connected with the main conduit and having a plurality of outlet openings adapted for connection of branch conduits thereto, continuously revolving means in the casing at all times in communication with the main conduit and operative to connect and shut off the main conduit with the outlets of the casing in successive sequence, a motor, and means to mount the motor on the exterior of the casing and operatively connect the same with

the revoluble means comprising a hollow hub arranged on the revolving means engaging an opening in the casing into which the motor shaft is extended and secured thereto, and a bearing member fixed to the exterior of the casing in which the motor shaft is mounted to rotate and held against axial movement.

5
